UNITED STATES PATENT OFFICE.

JOHN H. UHRIG, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY.

CENTRIFUGAL PIPE-CASTING MACHINE.

Application filed November 23, 1926. Serial No. 150,207.

My invention relates to centrifugal pipe casting machines and has for its main object to provide means for rotating the mold of such a machine which will leave the mold free to expand and contract without putting any injurious strains on the mold itself or on the driving mechanism. A further object of my invention is to combine loosely connected driving mechanism with a metal mold, the external conformation of which will approximately correspond with its internal form and which will be without the usual radial flanges which I have found to bring about injurious strains in the metal of the mold.

The general nature of my invention as well as specific features thereof will be best understood as described in connection with the drawings, which illustrate a centrifugal casting machine of the kind used in producing De Lavaud cast iron pipes and embodying the improvements which constitute my invention.

In the drawings, Figure 1 is a vertical elevation of the machine taken as on the line 1—1 of Fig. 2.

Figure 2 is an end view taken at the right hand side of Fig. 1 on a reduced scale, and

Figure 3 a sectional elevation on the line 30 2—2 of Fig. 1, also on a reduced scale.

A and A¹ are respectively the upper and lower sections of the casing of the machine, in which is formed a water jacket for the mold. B is the mold, having as shown, a bell end at B¹ and a spigot end B². As shown, the mold, which is formed of a steel forging, is formed with an end extension B³, constituting a core seat and formed with radial notches B⁴ to engage the driving dog to be described, B⁴ indicating key holes also formed in the core seat. As shown, the mold is formed with a shoulder B⁵ and a peripheral groove B⁶. The mold is rotatably supported in the casing on rollers indicated at I, I, and as shown, has secured to its spigot end by bolts indicated at M, a drum L, having packing grooves l, l, formed in it, the packing in which, indicated at P, forms a water tight joint with 50 the walls O and O¹ at the end of the casing. N is a terminal ring secured to the drum by bolts indicated at n.

C is a driving ring, having, as shown, a gear wheel C¹ formed on it and rotatably

supported on rolls, indicated at H, revolving 55 on ball bearings H¹ on the shaft G, which is firmly secured at the end of the casing. The supporting rolls H are so located as to support the axis of the ring in approximate coincidence with the axis of rotation 60 of the mold. As shown, the ring C is formed with a shoulder C² in position to abut against the shoulder B⁵ at the bell end of the mold and with an extension C³ which partly surrounds the mold shoulder B⁵. It 65 is also formed with an outwardly extending flange C⁴ adapted to fit against a bearing ring, indicated at R and fitting against an inwardly extending flange J¹ of the casing, the end indicated at J. The packing 70 F forms a water tight joint between the shoulder B⁵ and the extension C³. D is a ring secured to the extension C³ of the ring, as by bolts E, and having formed on it inwardly extending driving dogs D¹ which 75 extend into the notches B⁴ in the core seat extension of the mold. The ring D is also formed with an outwardly extending flange D² which fits against the flange J¹.

Q indicates a driving gear engaged with 80 the gear C¹. K is the end wall of the water jacket portion of the casing having as shown two inwardly extending portions K¹, K¹, against which fit packing rings k¹, formed as shown in a ring S, secured to the 85 inner end of the ring C.

By preference and as illustrated in the drawing, the connection between the driving ring and the mold is loose so that while the dogs D¹ engage the notches B⁴ and thus 90 enable the gear ring C to drive the mold, the mold is quite free to expand and contract without incurring any strains through its connection with the driving ring.

While I have illustrated what I believe 95 to be the best embodiment of my invention, I wish it to be distinctly understood that I do not wish to be understood as in any way limiting my claims to the specific construction shown in the drawings, as my invention is clearly capable of being embodied in many different forms of construction.

Having now described my invention, what I claim as new and desire to secure by Letters Patent is:

1. A centrifugal pipe casting machine having in combination a mold, means support-

ing the mold for revolution on its longitudinal axis, a rotatable mold driving ring located near one end of the mold, independent means for supporting said ring so that the 5 axis will approximately coincide with that of the mold, means for rotating said ring and means for coupling the driving ring to the end of the mold.

2. A centrifugal pipe casting machine having in combination a mold, means supporting the mold for revolution on its longitudinal axis, a rotatable mold driving ring located near one end of the mold, independent means for supporting said ring so that its axis 10 will approximately coincide with that of the mold, means for rotating said ring and means for loosely coupling the driving ring to the end of the mold so as to leave the mold free to expand or contract without shifting the position of the driving ring.

3. A centrifugal pipe casting machine having in combination a metal mold, means supporting the mold for revolution on its longitudinal axis, a water jacket casing surrounding the body of the mold, a rotatable mold driving ring located near one end of the mold (independent means of supporting said ring so that its axis will approximately coincide with that of the mold, means 25 for rotating said ring and means for coupling the driving ring to the end of the mold.

4. A centrifugal pipe casting machine having in combination a metal mold, means supporting the mold for revolution on its longitudinal axis, a water jacket casing surrounding the body of the mold, a rotatable mold driving ring located near one end of the mold, independent means for supporting said ring so that its axis will approximately 30

coincide with that of the mold, means for 40 rotating said ring and means for loosely coupling the driving ring to the end of the mold so as to leave the mold free to expand or contract without shifting the position of the driving ring.

5. In a centrifugal pipe casting machine a metal mold having an external conformation corresponding to its internal form and substantially without radial flanges at its ends, means supporting the mold for revolution on its longitudinal axis, a rotatable mold driving ring located near one end of the mold, means for supporting said ring so that its axis will approximately coincide with that of the mold, means for rotating said 50 ring and means for loosely coupling the driving ring to the end of the mold so as to leave the mold end free to expand and contract.

6. In a centrifugal pipe casting machine a metal mold having an external conformation corresponding to its internal form and substantially without radial flanges at its ends, a core seat extension at the end of the mold formed with radial notches to engage driving dogs, means supporting the mold for revolution on its longitudinal axis, a rotatable mold driving ring located near one end of the mold, means for supporting said 65 ring so that its axis will approximately coincide with that of the mold, means for rotating said ring and means consisting of inwardly extending dogs secured to the end of the ring and engaged with the notches in the core seat for loosely coupling the ring to the mold.

JOHN H. UHRIG.
